(57) **CLAIM**

The ornamental design for a console for automobile, as described and shown.

DESCRIPTION

This patent application claims the benefit of Japanese Patent Application No. D-2003-016904, filed Jun. 16, 2003, which is incorporated by reference.

FIG. 1 is a front view of a console for automobile of the present invention.

FIG. 2 is a left side view of the console for automobile of FIG. 1.

FIG. 3 is a right side view of the console for automobile of FIG. 1.

FIG. 4 is a rear view of the console for automobile of FIG. 1.

FIG. 5 is a top plan view of the console for automobile of FIG. 1.

FIG. 6 is a bottom view of the console for automobile of FIG. 1.

FIG. 7 is a perspective view of the console for automobile of FIG. 1.

FIG. 8 is a front view of the main body of the console for automobile of FIG. 1.

FIG. 9 is a left side view of the main body of the console for automobile of FIG. 1.

FIG. 10 is a top plan view of the main body of the console for automobile of FIG. 1.

FIG. 11 is a perspective view of the main body of the console for automobile of FIG. 1.

FIG. 12 is a front view of the removable top portion of the console for automobile of FIG. 1.

FIG. 13 is a left side view of the removable top portion of the console for automobile of FIG. 1.

FIG. 14 is a top plan view of the removable top portion of the console for automobile of FIG. 1.

FIG. 15 is a perspective view of the removable top portion of the console for automobile of FIG. 1; and,

FIG. 16 is a reference view showing the top portion and the main body of the console for automobile of FIG. 1.

The broken line showing of the environment is for illustrative purposes only and forms no part of the claimed design.
